NARROW WARE LOOM

Frank W. Preston, Paterson, N. J.

Application May 13, 1939, Serial No. 273,437

3 Claims. (Cl. 139—138)

This invention relates generally to narrow-ware looms characterized by an auxiliary batten structure including superposed shuttle-races for corresponding banks of shuttles and capable of up or down movement on selection, as by a pattern means, so that, if desired, first one and then another of the banks (they carrying different colors or other qualities of weft) may serve some single bank of warp-sheds. When any one shuttle bank is brought to the weaving plane it should be driven independently of the others, wherefore the Ryon Patent No. 781,967 discloses a mechanical motion comprising coaxial independently driven cams, connected respectively with the shuttle banks, and a constantly rotated driver which is movable axially, as by pattern means, to position to drive any one independently of the other cams.

My invention is an improvement on this Ryon mechanism, but in order to explain wherein it is so it may be well first to allude to that mechanism more in detail. Each cam is characterized by four peripheral toothed segments alternating with concave peripheral plain or dwell segments. The driver has a peripheral toothed section to mesh and coat with that one of the toothed segments of the cams with respect to which it has been axially positioned for that purpose, but all the rest of its perimeter is cylindrical. On each quarter-revolution the driver rotates one cam a quarter-revolution while maintaining the others at dwell, but during the remainder of its complete cycle it maintains all the cams at dwell—by the engagement of its cylindrical surface with their dwell segments. Any quarter-revolution of a cam produces a movement one way or the other of the corresponding shuttle-bank, the actuating part of the cam for this purpose being 8-shaped, as an 8-shaped groove.

In order for the driver to put a cam in motion it is necessary that at least the leading end tooth of the driver's toothed section be formed larger than the others, the cam having a correspondingly enlarged recess to receive it. Under the constant impact of this tooth with the cams it frequently is broken off, which puts the whole system out of commission. Occasionally more of the driver than merely this tooth is damaged. As the Ryon system is constructed it is a tedious and time-wasting operation to remove the driver and either replace it with a new one in case it is an integral structure or replace the defective section thereof. One object of this invention is therefore to improve the system in question by so constructing the driver that it may be repaired with-

out bodily removal thereof and that it may be readily convertible for actuating any one or two or more cams at a time.

In the drawing,

Fig. 1 is a side elevation, partly in section, and Fig. 2 a right-hand elevation of the improved system;

Fig. 3 is a right-hand elevation of the driven body; and

Fig. 4 is an isometric view of a dwell segment.

Let 1 be identical cams independently revolvable around a suitably supported horizontal shaft 2 and suitably spaced apart. Each cam has equal-length peripheral toothed segments 3 and alternating therewith peripheral concave plain or dwell segments 4, there being an enlarged space 3a between each dwell segment and each toothed segment thereto adjoining. Each cam also has formed around its axis a camway 5, as a groove, generally 8-shaped. With this camway engages a part of a lever 6, as a roller 6a thereon, which lever is to be connected by means 7 with some medium for transmitting movement to the rack or equivalent for driving that one of the shuttle-banks which appertains to the particular cam, all as in the said Ryon patent. The levers 6 alternate with the cams.

On a shaft 8 parallel to shaft 2 and suitably constantly rotated in one direction is my improved driver, splined to the shaft so that it may be shifted axially thereof. This driver is constructed as follows:

A cylindrical body 9, having the splined connection with the shaft, and also having an extension sleeve 9a formed with a peripheral grooved head 9b by which it may be shifted axially, has a sector-shaped recess 10 formed therein which in this example extends from near one end to near the other end thereof, whose arcuate extent at the perimeter of the body approximates 120°, and whose radial extent is here from the bore of the body to its perimeter.

Four sector-shaped elements are simultaneously to occupy this space, being all of equal width. These may be selected from a set of seven of them, or four, as 11, having toothed perimeters 11a, and three, as 12, having plain perimeters 12a; the terminal teeth 11b of the toothed elements are enlarged, being adapted to engage in the recess 3a of the toothed segments 3 of the cams. When any one of the elements of the class 12 occupies the recess 10, its arcuate surface is exactly in the same radius as the cylindrical surface of the body 9; when any one of the class 11 occupies the recess its teeth project be-

yond such radius or so as to mesh properly with the teeth of any cam. All the elements are here of equal width.

For securing the segments in place in the recess the body 9 has extensions 13, as rabbets, of such recess extending therefrom in opposite directions around the axis and next to the perimeter of the body and each element 11 and 12 has lugs 14 to enter these recesses, screws 15 being driven through the lugs and into the body. Of course the toothed portions of the elements 11 are formed to mesh and otherwise coact properly with those of the cams. Thus if any tooth or other portion of the driver breaks or becomes otherwise unserviceable the sector affected may be replaced by another without disturbing any of the rest of the system.

The possibility of actuating any one, two or more cams constantly, or first one and then the other of any two, or first one and then the other of any pair, is simply a matter of properly positioning in the recess 10 the toothed elements 11 or the appropriate elements 11 and 12.

I do not wish it to be understood that the elements occupying the recess 10 at any time are necessarily separable from each other rather than as forming a unitary, as an integral, structure or device. Suffice it to say, therefore, that the invention contemplates the driver having a sector-shaped recess, as 10, opposed to and at least approximately as wide as the group of cams and by which a sector-shaped device having peripheral teeth to mesh with at least one of the cams is filled and means to removably secure such device in the recess. Supporting structure for the shafts 2 and 8 and in which the levers 6 are fulcrumed is shown at 16.

Having thus fully described my invention, what I claim is:

1. In combination, with supporting structure and, journaled therein, a group of identical coaxial and generally circular independently rotatable cams for imparting reciprocation to respective shuttle-banks of a loom, each cam having at its perimeter four equal-length toothed segments alternating with four equal-length concave dwell segments, a constantly rotating driver

journaled in said structure with its axis parallel to that of the cams and including, with a cylindrical member opposite the cams and having such radius that its perimeter will enter any dwell segment of any cam when such segment is presented thereto and also having recessed a sector thereof which is in the same zone, and axially of said member is at least approximately as wide, as said group, a sector-shaped device filling said recess and having a toothed perimeter within the same zone as and arranged to mesh with and having substantially the same length as the toothed segments of any of the cams, and means to secure said device removably to said member. 5

2. In combination, with supporting structure 15 and, journaled therein, a group of identical coaxial and generally circular independently rotatable cams for imparting reciprocation to respective shuttle-banks of a loom, each cam having at its perimeter four equal-length toothed 20 segments alternating with four equal length concave dwell segments, a constantly rotating driver journaled in said structure with its axis parallel to that of the cams and including, with a cylindrical member opposite the cams and having such 25 radius that its perimeter will enter any dwell segment of any cam when said segment is presented thereto and also having recessed a sector thereof which is in the same zone, and axially of said member is at least approximately as wide, as said 30 group, a group of equal-width separable sector-shaped bodies filling said recess and at least one of which is arranged in the same plane as, and has a toothed perimeter arranged to mesh with and of substantially the same length as the 35 toothed segments of, any of the cams, and means to secure said bodies removably to said member.

3. The combination set forth in claim 2 characterized by said member having rabbets adjacent to its periphery and respectively reaching 40 from the recess in opposite directions crosswise of the axis of the driver and by said bodies having oppositely projecting lugs arranged to enter said rabbets and by said securing means being screws driven through the lugs into said member. 45
